UNITED STATES PATENT OFFICE.

JAMES KENT REYNARD, OF NEW YORK, N. Y., ASSIGNOR TO HIMSELF, AS TRUSTEE.

SOUND-RECORD AND MEANS AND METHOD FOR PRODUCING THE SAME.

1,283,903.

Specification of Letters Patent.

Patented Nov. 5, 1918.

Application filed April 19, 1918. Serial No. 229,630.

To all whom it may concern:

Be it known that I, JAMES KENT REYNARD, a citizen of the United States of America, residing at New York, N. Y., have invented 5 new and useful Sound-Records and Means and Methods for Producing the Same, of which the following is a specification.

My invention relates to a new and improved sound record for phonographs and 10 the like, and also to a new means for producing such a record. My object is to produce a record having a groove of unique and advantageous characteristics.

At the present time there are three types 15 of grooves. One is known as the "hill and dale" type; another as the "zig-zag" type; and a third is referred to as the oblique cut or "Emerson" type.

In order to use records having the "hill 20 and dale" cut to the best advantage, it is essential that the diaphragm of the reproducing instrument should be placed in a plane inclined obliquely to the surface of the record and extending transversely of 25 the line or direction of the groove so that the point of the needle or stylus may freely and accurately trail over the undulations of the bottom of the groove, whereby it will impart corresponding vibrations to the dia- 30 phragm.

In order to use a groove of the "zig-zag" type to the greatest advantage it is essential 35 that the reproducing diaphragm shall be placed in a plane substantially vertical to the plane of the record and as closely as possible in, or parallel to, the line of travel of the record groove under the stylus, whereby the opposite side walls of said groove will uniformly engage the sides of 40 the stylus near the point to impart the proper vibrations to said diaphragm. While it is possible in some instances to place the diaphragm in a different position, in connection with its use with a groove of the 45 "zig-zag" type, and to thereby secure sound reproduction, such reproduction is very subdued in volume and is inferior and wholly unsatisfactory from the standpoint of artistic merit.

50 The aforesaid oblique cut, or "Emerson" type of groove, may be said to be a compromise between the "zig-zag" and the "hill and dale" types of grooves which makes it possible to use a diaphragm placed in either 55 of the aforesaid positions and to get approxi-

mately the same results in either position so far as sound reproduction is concerned, but at a sacrifice of quality and detail as compared with the results attained by the use of either one of the first mentioned types 60 of grooves. It is neither a full "hill and dale" nor a full "lateral" cut.

It is my purpose to construct a cut which, instead of being a compromise between the two first mentioned types of grooves at the 65 sacrifice of quality or detail, might be referred to as a composite of both the "hill and dale" and the "zig-zag" grooves so that a reproducing diaphragm may be used therewith in either of the aforesaid positions or 70 in any intermediate position, with substantially equally good results and substantially as good results as are obtained by the use of a strictly "hill and dale" groove or a "lateral" groove, and without sacrifice to 75 quality or detail in sound reproduction. As a result of my improvement I may produce a disk record which may be used to the utmost satisfaction with a phonograph equipped with a sound box especially de- 80 signed and positioned for use for a record having a "hill and dale" groove, or with another phonograph equipped with a sound box especially designed and positioned for a record having a "zig-zag" groove. 85

In the accompanying drawing:

Figure 1 is a plan view of a record of the disk type, the same being conventionally shown.

Fig. 2 is a view of the essential parts of 90 the music recording or groove cutting means, these parts likewise being conventionally shown and diagrammatic in character.

Fig. 3 is a plan view of a short length of 95 the record groove conventionally shown, and greatly enlarged.

Fig. 4 is a longitudinal section through said groove on the dotted line 4—4 of Fig. 3.

Fig. 5 is a cross section of the groove on the line 5—5 of Fig. 3. 100

Fig. 6 is a cross section of the groove on the line 6—6 of Fig. 3.

Fig. 7 is a diagrammatic view including part of a diaphragm and platen in which latter part of the record groove is shown as 105 having been engraved.

Referring to Figs. 2 and 7, 1 represents the diaphragm designed to receive the sound waves which are utilized for making the record groove. 2 conventionally represents 110

2

the cutter of the instrument by which the groove is formed. In the particular form shown, this cutter is conventionally shown as a needle. This cutter 2 is rigidly mounted on a carrier 3 which is hinged at 4 at one side of the cutter point relatively to the direction of the groove to be formed. 5 represents a connection between the diaphragm 1 and the carrier 3. The cutter 2 is mounted 10 on the carrier at a point away from the hinged point 4 and preferably between the connection 5 and the pivot 4 as shown in Fig. 2. It follows that when the diaphragm 1 vibrates to and fro it will impart a positive to and fro endwise movement to the cutter, and it also follows that while the cutter is vibrating to and fro the point thereof will likewise be caused to positively vibrate laterally; hence, if the cutting point 15 of the cutter 2 is in engagement with the material in which the groove is to be cut, it will obviously form therein an undulation groove of uneven depth like the so-called "hill and dale" type of cut as well as 20 a laterally undulating groove like the so-called "zig-zag" type of cut. Of course, if the cutter is forced deeply into the material of the platen in which the groove is being formed, the width of the groove at the 25 surface of the platen will be slightly greater than in the case of a shallow cut, this being due to the tapering sides of the cutter, and to this extent the outline of the groove (at the surface) will vary somewhat from the 30 outline of the true "zig-zag" groove (at the surface) which is always of the same width since it is always of uniform or constant depth, but this is of no material consequence because the effective part of the groove, when 35 it is being used with a reproducing needle is close to the bottom and narrow (whether that part of the groove is shallow or deep), and this part of the sides of my new groove 40 where the needle engages always very closely conforms to the true "zig-zag" cut. That 45 this must be the case with a cutter such as illustrated in Fig. 2 is obvious. The parallel dotted lines in Fig. 3 illustrate the effective sides of the groove for sound reproducing purposes, and the undulations produced 50 by the sound waves occur on the bottom and on the opposite sides of the effective part of said groove simultaneously and correspondingly.

55 Because the particular shape of any sound producing groove is ever varying, it is practically impossible to accurately illustrate the same by means of a pen and ink drawing, particularly because many of the sound waves or vibrations are so microscopic as to be almost beyond the possibility of human recognition. Accordingly, it should be understood that the several illustrations of the groove found in the accompanying drawings 60 are merely graphic to illustrate the gen-

eral principle and must not be regarded as definite either as to shape or proportion. In the said drawings, I have attempted to show a wave of substantially uniform amplitude and period formed in both of the side walls 70 of the groove and also in the bottom of the groove, and it is obvious that the same principle will be followed out in vibrations of different amplitude and period. The full amplitude of a single vibration is approximately 75 illustrated by that part of the groove between the lines 5-5 and 6-6 of Fig. 3, and it will be observed that at the line 5-5 the groove is deeper than at the line 6-6, that is because the point of the recording 80 cutter 2 as it is forced forward and laterally by the diaphragm makes a deeper and a wider gouge in the material than when the diaphragm retracts and retracts the point of the cutter for forming that part of the groove 85 at the line 6-6. Since the effective part of the groove for side engagement of a reproducing stylus, such for example as indicated at 6 in Figs. 5 and 6, is always close to the bottom, it follows that the lateral 90 groove, by which I mean the effective part thereof, is of substantially uniform width and therefore possesses that characteristic of the strictly lateral or zig-zag type of groove. These lateral undulations also are 95 reproduced in the bottom of the groove and hence the bottom of the groove is ever varying or non-uniform in depth, thus corresponding to the strictly hill and dale type of groove from which it follows that my 100 new and improved groove is in reality a composite (rather than a compromise) of both of the aforesaid types of cuts and will successfully and satisfactorily operate with either of the aforesaid types of phonographs without sacrifice to either detail or 105 quality, provided of course the record is well made.

Since the complementary undulations in both series occur in substantially the same 110 transverse position in the groove, it is apparent that when a reproducing needle is being actuated by one series of undulations, say the hill-and-dale series, there will be no interference occasioned by the other series 115 and vice versa.

In operation: It is obvious that if the stylus of a reproducing instrument is positioned exactly in a vertical plane extending longitudinally of the groove, it will trail 120 along the undulations in the bottom of the groove, and will simultaneously be vibrated laterally to the same extent. Thus, it matters not whether the sound reproducing diaphragm is arranged in a plane transverse to 125 the groove or in line, or parallel, with the groove since the sound waves represented by the varying undulations will be transmitted thereto for sound reproduction in accordance with said vibrations. It is a well 130

known fact that with even a hill and dale record it is possible to secure some degree of sound with the diaphragm positioned as for a lateral or zig-zag cut or vice versa, but of course in such a case the volume is reduced and much of the detail is missing. Nevertheless, the very fact that some degree of sound is produced under such conditions is useful in reproducing sound by means of my improved groove because, irrespective of the positioning of the diaphragm relatively to the groove, both sets of undulations, that is to say, the hill and dale set and the lateral set, simultaneously contribute to the production of sound. So also, if the diaphragm should be placed obliquely instead of either transverse to, or parallel with, the groove, the sound will be reproduced in accordance with both sets of vibrations, each set contributing its share to said reproduction depending upon the particular angle or pitch of said diaphragm. When the angle of the diaphragm is oblique, as I have just mentioned, the angle of the reproducing stylus is also pitched out of a vertical plane so that it in turn stands obliquely to the groove, the upper part of the groove affording sufficient clearance therefor so that the said stylus may work properly. Where the angle of the stylus is pitched obliquely as last mentioned there will be more side engagement on one side of the groove than on the other, but I have found that this will not materially interfere with the proper functioning of the stylus if the record is well made and cleanly cut so that it will have smooth and well defined surfaces. While it is more difficult to produce a groove of the hill and dale or varying depth type so that it will possess smooth and well defined surfaces, nevertheless, by the exercise of proper care and the selection of an appropriate cutting tool, I have been able to produce this type of groove so that it will reproduce sound with entire satisfaction and without sacrifice of quality or detail.

In Fig. 7 I have diagrammatically shown how the needle or recording stylus will operate to produce two independent substantially corresponding series of undulations in the bottom and in the opposite side walls of the groove being formed in the platen P and in which groove the complementary undulations in both series are bound to occur in the same location transversely of the groove, so that the undulations of one series will not interfere with the operation of a reproducing needle when being influenced by the undulations of the other series. It will be noted that the point of the needle moves on the arc $g-g$ as the diaphragm 1 is flexed, hence, the point of the needle has a positive lateral movement (relatively to the direction of the groove being formed) between the lines $e-e$ and $f-f$ and a corresponding positive

endwise movement between the lines $a-a$ and $b-b$ thereby at once producing two independent and substantially corresponding series of sound reproducing undulations.

What I claim is:

1. In a sound record of wax or other suitable material, a record groove therein, comprising two independent substantially corresponding series of undulations formed respectively in the bottom and in the opposite side walls thereof adjacent to said bottom, both series being synchronized, the complementary undulations in both series occurring in the same location transversely of the groove whereby either series may be used to reproduce sound waves without interference by the other series. 75

2. Means for forming a record groove in a surface of wax or other suitable material, comprising a pointed cutter, means for mounting said cutter whereby the same may be caused to move endwise into said material and whereby the point may be caused to simultaneously move laterally relatively to the direction of the groove being formed 85 to produce two independent substantially corresponding series of synchronized undulations in the bottom and side walls thereof, and a single sound responsive means for imparting both movements to such cutter simultaneously. 90

3. Means for forming record grooves in the surface of wax or other suitable material comprising, a cutter, a sound responsive diaphragm, a carrier for the cutter, said carrier being mounted at one side of the groove to be formed to have an oscillating movement, said cutter being connected to said carrier at a point remote from the axis of oscillation, and a connection between said carrier and said diaphragm whereby the vibrations of the diaphragm will be transmitted to the point of the cutter through the medium of said carrier and whereby a combined lateral and endwise movement will be 105 imparted to the end of said cutter. 100

4. Means for forming a record groove in the surface of wax or other suitable material comprising, a cutter, means for mounting said cutter comprising a carrier hinged 115 at one side of the cutter point relatively to the direction of the groove to be formed, with means for imparting movement to the carrier to cause the cutting point thereof to move depthwise into the material in which 120 the groove is being formed to a varying degree and to simultaneously move laterally relatively to the general direction of the groove being formed to produce both vertical and lateral undulations. 125

5. Means for forming a record groove in the surface of wax or other suitable material comprising, a cutter, means for mounting said cutter comprising a carrier hinged at one side of the cutter point relatively to the 130

4

direction of the groove to be formed, with a single means for imparting movement to the carrier to cause the cutting point thereof to move depthwise in the material in which the 5 groove is being formed to a varying degree and to simultaneously move laterally relatively to the general direction of the groove being formed to produce both vertical and lateral undulations, said undulations being 10 deeper and wider on the side nearest the axis of the cutter and shallower and narrower on the remote side.

6. The method of forming a record groove in wax or other suitable material, comprising forcing a suitable cutting medium by 15

means of a single sound-responsive device into the surface of a moving body of wax or the like, and imparting thereto a simultaneous and substantially corresponding endwise and lateral movement relatively to 20 the direction of the groove being formed to produce two independent series of substantially corresponding vertical and lateral undulations in the bottom and sides of said groove respectively, with the complementary undulations of both series occurring in 25 the same location considered transversely of the groove.

JAMES KENT REYNARD.
